UNITED STATES PATENT OFFICE

DESIGN FOR A COMBINED SAUCE KETTLE AND COVER

Alexis de Sakhnoffsky, Philadelphia, Pa., assignor to The Vollrath Co., Sheboygan, Wis., a corporation of Wisconsin

Application January 22, 1934, Serial No. 50,467

Term of patent 7 years

To all whom it may concern:

Be it known that I, ALEXIS DE SAKHNOFFSKY, a subject of the Czarist regime of Russia, residing at Philadelphia, in the county of Philadelphia and State of Pennsylvania, have invented a new, original, and ornamental Design for a Combined Sauce Kettle and Cover, of which the following is a specification, reference being had to the accompanying drawing forming a part hereof.

Fig. 1 is a side elevation of a combined sauce kettle and cover, embodying my design;

Fig. 2 is a bail-end elevation thereof;

Fig. 3 is a plan view thereof taken on the line 3—3 of Fig. 1; and

Fig. 4 is an enlarged detail section through the rim taken on the line 4—4 of Fig. 1.

The shading on the drawing serves the two-fold purpose of indicating surface contour and of indicating a contrasting and darker color than that of the unshaded surfaces.

I claim:

The ornamental design for a combined sauce kettle and cover as shown and described.

In witness whereof, I hereunto subscribe my name this 18th day of January, 1934, at Chicago, Illinois.

ALEXIS DE SAKHNOFFSKY.
